UNITED STATES PATENT OFFICE.

ERWIN MOHN, OF ROCHESTER, MINNESOTA.

ELECTRICALLY-OPERATED SIGN.

Application filed January 16, 1928. Serial No. 246,981.

My present invention relates to electrically operated signs and has for an object to provide a rotatably mounted ball upon the surface of which may be displayed any suitable exhibiting indicia or device tending to enhance the attractiveness of the sign during the rotation of the ball and providing electro-magnetic operating means for the ball for rotating the same upon a vertical axis.

A further object is to provide a pair of retainer plates for rotatably supporting the ball, one of the plates having a stator mounted therein setting up a primary magnetic field and the ball having a coil forming a secondary magnetic field and responsive to the force of the primary whereby to cause the rotation of the ball.

Another object is to arrange the coil in the ball, constituting the rotor, responsive to the current passing through the stator so as to utilize the same for supplying current to a plurality of electric light bulbs mounted on the surface of the ball, and which may be arranged to create various display effects during the rotation thereof.

An additional object is to provide the retainer plates of an area substantially greater than the surface of the ball contacting there-with whereby to permit the ball to travel a circular path between the plates during its rotary movement.

A still further object is to provide a sign of this character of simple and practical construction, efficient and reliable in performance, neat and attractive in appearance, inexpensive to manufacture and otherwise well adapted for the purposes for which the same is intended.

Other objects and advantages reside in the special construction and combination of the various elements comprising the invention, reference being had to the accompanying drawings forming a part hereof, wherein:

Figure 1 is a side elevational view showing the assembled sign mounted in operative position,

Figure 2 is a sectional view through the ball showing the coil constituting the secondary winding,

Figure 3 is a similar view showing the winding in cross section,

Figure 4 is a top plan view of the lower retainer plate and support therefor,

Figure 5 is a similar view with the retainer plate removed showing the coils constituting the primary, one of the coils being sectional,

Figures 6 and 7 are details of the primary coil attaching brackets, representing end and side views respectively,

Figure 8 is a sectional view of the ball showing the light connections with the secondary,

Figure 9 is a perspective view of one of the light attaching sockets,

Figure 10 is a similar view of the moisture-tight washer for the bulb,

Figure 11 is an elevational view of an assembled sign showing a plurality of reflecting mirrors substituted for the lights upon the surface of the ball,

Figure 12 is a similar view of a slightly modified form of sign, and

Figure 13 is a perspective view of one of the mirrors.

Referring to the drawings in detail the invention comprises a ball 5, constructed either of solid material or sections suitably secured together and supported for rotation between upper and lower retaining plates 6 and 7 respectively. The plates are secured upon bracket arms 8, and 9 respectively, providing means for fixedly attaching the same.

The plates are of insulation material and are dished or concaved as indicated at 10 to retain the ball therebetween, the concaved area being considerably larger than the contacting surface of the ball thus permitting the ball to move in a horizontal plane. The lower plate 7 is provided with a drain opening 11 to prevent the accumulation of water therein.

The outer edge 12 of the lower plate is supported upon a framework 13 attached to the arm 9, said framework including a plurality of spaced parallel supports 14 having clamping plates 15 adapted to engage the opposite sides of an angular electro-magnetic core 16. The core is formed of a plurality of laminations 17 having their ends disposed at angles of 120° and assembled in a manner as shown in Figure 5 to provide a unitary core having three arms extending horizontally from a common center at a uniform

angle. Bolts 18 extend transversely through the laminations and provide a connection for the support 14 with the clamping plates 15.

Coil windings 19 are arranged about each 5 of the arms of the core having separate electrical connections 20 with a suitable source of current, thus forming a primary coil assembly disposed beneath the lower plate 7 upon which the ball 5 is mounted.

10 Within the ball, below the center thereof is a hole 21 forming a housing for a horizontally disposed secondary coil composed of an armature core 22 also composed of a series of laminations or if desired constructed 15 of a solid piece of material and about which is wound the coil winding 23. The secondary coil is disposed so as to respond to the magnetic force of the primary coils and accordingly upon connecting the same to a three-phase source of supply a rotating magnetic field is set up part of which will pass through the secondary or rotor core and tend to rotate the ball.

Extending radially from the secondary 25 coil is a plurality of bores 24 communicating with the outer surface of the ball and terminating at different horizontal planes and at various circumferential positions thereon, with electric light sockets 25 secured therein 30 by brackets 26. Light bulbs 27 are mounted in the sockets, a packing washer 28 being provided about the bulb to prevent moisture from entering the bore. Connection is made between the coil winding 23 and the bulb by 35 wires 29 and 30 attached respectively to the socket and base of the bracket to which the base of the bulb contacts. By transformer action a sufficient voltage is induced in the rotor coil which is utilized to illuminate the 40 filament in the bulbs 27.

The primary and secondary coils are properly wound to cause the rotor to spin on a vertical axis at a rapid rate which imparts to the moving bulbs 27 the appearance of a 45 continuous streak of light circumscribing the ball.

Furthermore due to the angular position of the various coils of the primary and the enlarged area of the retaining plates, the ball 50 will travel in a circle within the concaved surface of the plates, which from a position at a horizontal plane with the ball will indicate a reciprocating movement back and forth along the plates.

55 In lieu of the bulbs 27, the surface of the ball may carry a plurality of reflecting mirrors 31 secured to an attaching bracket 32 by a rigid link member 33 permitting the mirror to be arranged in suspended relation upon the ball and upon the rapid rotation thereof to move upward to a horizontal plane with the bracket 32 due to the centrifugal force imparted to the suspended mirrors. One or more stationary electric light 60 bulbs 34 may be arranged adjacent the ball 65

adapted to focus upon the mirrors, the latter reflecting the light therefrom.

The sign thus produced is admirably adapted for use by theatres, cafés and the like as an attractive and distinctive identifying feature. 70

It is obvious that the invention is susceptible of various changes and modifications, without departing from the spirit or scope of the invention or sacrificing any of its advantages, and I accordingly claim all such forms of the device to which I am entitled. 75

Having thus described my invention, what I claim as new is:

1. A device of the class described comprising, a rotor, a pair of retaining plates rotatably supporting the same, a secondary coil carried by the rotor and a primary coil carried by one of said plates and arranged in operative position with each other, illuminating means mounted on the surface of the rotor and connected for operation through said secondary coil, said primary coil being adapted for rotatably moving said rotor about a vertical axis and to cause a circular movement thereof in a horizontal plane. 80

2. A device of the class described comprising, a rotor, a pair of retaining plates rotatably supporting the same, a stator comprising a three phase primary coil with its respective fields disposed in a horizontal plane with each other and arranged in an equidistant angular relation with each other, a secondary coil carried by the rotor in operative relation with the primary for moving the rotor about a vertical axis in a horizontal circle and illuminating means mounted on the surface of the rotor connected for operation with said secondary coil. 95

3. In a device of the class described, a 100 rotatable member having a free axis, electro-magnetic operating means spaced from the member, an electro-magnetic responsive means eccentrically arranged in said member whereby to provide for the rotation 110 thereof in a predetermined plane and illuminating means mounted on the member and arranged for energization by said operating means.

4. In a device of the class described, a 115 rotatable member having a free axis, electro-magnetic operating means spaced from the member, an electro-magnetic responsive means eccentrically arranged in said member whereby to provide for the rotation 120 thereof in a predetermined plane and illuminating means mounted on the member and arranged for energization by said operating means, said responsive means providing a circuit connection for the illuminating 125 means with said operating means.

5. In a device of the class described, a stator comprising a series of radially disposed primary coils, a rotor spaced from the stator having a free axis and a secondary 130

coil eccentrically arranged in the rotor and responsive to the primary coil whereby to rotate the rotor in a predetermined plane and 10 responsive to the primary coil whereby to rotate the rotor in a predetermined plane.

6. In a device of the class described, a 5 stator comprising a series of radially disposed primary coils, a rotor spaced from the stator having a free axis, a secondary coil eccentrically arranged in the rotor and re-

sponsive to the primary coil whereby to rotate the rotor in a predetermined plane and 10 electrically energized illuminating means mounted on the surface of the rotor and operatively connected with the secondary coil for energization by the primary coil.

In testimony whereof I affix my signature.
ERWIN MOHN.
